US0D1103607S

(12) **United States Design Patent** (10) **Patent No.:** **US D1,103,607 S**
(45) **Date of Patent:** **** Dec. 2, 2025**

(54) **SHOE**

(71) Applicant: **SHENZHEN STARLINK
NETWORK TECHNOLOGY CO.,
LTD, Shenzhen (CN)**

(72) Inventors: **Jie Huang, Shenzhen (CN); Patricia
Thaina Da Cunha Sander, Shenzhen
(CN)**

(**) Term: **15 Years**

(21) Appl. No.: **30/015,544**

(22) Filed: **Jul. 29, 2025**

Related U.S. Application Data

(62) Division of application No. 29/950,758, filed on Jul. 4, 2024.

(51) **LOC (15) Cl.** **02-04**

(52) **U.S. Cl.**

USPC **D2/971**

(57) **CLAIM**

The ornamental design for a shoe as shown and described.

DESCRIPTION

FIG. 1 is a perspective view of a shoe showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines and the areas within depict portions of the shoe that form no part of the claimed design. The figures include textured portions, which are designed to show a stitched fabric of the embodiment's design.

1 Claim, 8 Drawing Sheets
